George Tibbitts, Junior.

Letters Patent.

The subject referred to in these letters Patent and making part of the same contains
a description in the words of the said George Tibbitts Junr., himself of his im-
provement in constructing Cisterns.

Moving dug a circular pit of a suitable size, place within it over
the outside a tier of planks of any suitable length and thickness, bevelled so that
when brought close together, they will form a circular tube, around the outside of
this tube the earth or some other hard substance should be packed even with the
top upon the bottom of the pit around the inside of this tube, spread a stratum
of mortar of water, lime, and sand, upon which place another tier of planks
or boards prepared in like manner as the first, so as to form another tube with
in the first above mentioned of so much less top as to leave a space open one
to two inches in width between them, this space is to be filled with gravel (a
composition of water lime sand and water so thin as to run) so in places where
lime and water lime are plenty. This space may be form dug to twelve inches
wide and filled with small stone or gravel and rounded so that the gravel has
become sufficiently hard (which will require but a few minutes if the lime is good)
The inside and top of the last mentioned tube should be plastered with mortar of
the materials above mentioned, so as to exclude all the sand and exclude from it the
air and water. The bottom of the pit should then be plastered with lime
mortar, then covered with a stratum of stone or brick and gravel or plastered
again with mortar of the materials aforesaid. This done the whole should be
covered so as to exclude from pit. The invention or improvement of which the
petitioner claims to be the author is the using his tubes and filling the space between
them with gravel stone or gravel & gravel and excluding the air and water from
the inner tube, whereby it is preserved from decay and the effects of worms.

In witness whereof the petitioner above named have hereunto set my
name the first day of December 1833.

George Tibbitts, Junr.
